DESIGN FOR A GIRDLE

Ralph A. Greco, New York, N. Y., assignor to La Vivante Foundations Inc., a corporation of New York

Application March 7, 1940, Serial No. 90,745

Term of patent 7 years

To all whom it may concern:

Be it known that I, Ralph A. Greco, a citizen of the United States and a resident of the city of New York, county of Bronx and State of New York, have invented a new, original, and ornamental Design for a Girdle, of which the following is a specification, reference being had to the accompanying drawing, forming part thereof.

The single figure of the drawing is a front elevational view of a girdle showing my new design, the rear of the garment being conventionally plain.

I claim:

The ornamental design for a girdle, as shown and described.

RALPH A. GRECO.
